BOTTLE CASE

James H. Crnickshank, New York, N. Y.

Application August 3, 1931, Serial No. 554,652

4 Claims. (Cl. 217—19)

The invention relates to bottle-cases and more particularly to open-bottom cases for milk bottles.

Its main object is to provide a case or crate which will meet all the requirements for a suitable container of bottles and not only some of them, as do the bottle-cases now on the market. A feature of this invention is a novel self-contained open-bottom for the case, forming a separate unit which may be readily assembled and secured to the side-walls of the case without any nail or screw fastening, which is much stronger and durable than the bottoms of the known cases and which may be easily removed as a whole for repair and replacing.

This novel open-bottom may be formed by longitudinal strips of timber alternating with parallel metal wires carried and held fast together by a channel member lying on one side with its open part facing the inside of the bottom and running either all around the bottom or along the two end-sides thereof, or it may comprise a netting of wires riveted to a channel member running all around the bottom of the case.

Another feature is to form with this novel open-bottom and four upright guide-members, without using any special fastening means, a self-supporting skeleton-frame, facilitating the building of the side-walls of the case.

This skeleton-frame, in one form of the invention, may be made more rigid by having each pair of said upright guide-members made integral with the channel-member of the bottom at each end-side of the case.

A further feature of the invention is the provision of a partitioning inner-frame of a novel construction, which makes it very convenient, durable, easy of repair and economical both in manufacture and in use, as it reduces the breakage of bottles and the consumption of ice.

This inner frame may be made entirely of wood, or of wooden posts conveniently tied together and kept at the proper spacing by metallic wires, riveted to the side-walls of the case, or also entirely of bands or straps of spring-steel arranged so as to form within the case a plurality of resilient bottle-holders.

Other features and advantages will hereinafter appear.

In the accompanying drawings:

Figure 1 is a front view of a first embodiment with part broken to show the interior of the case and part in section on line 1—1 of Figure 2, without the side-walls of the case to show the

skeleton formed by the bottom and the four reinforcing corners.

Figure 2 is a top view with part broken to show the bottom of this first embodiment.

Figure 3 is a top view at smaller scale of a second embodiment with part of the side-walls broken to show the bottom of the case.

Figure 4 is a section on line 4—4 of Figure 3 and Figure 5 a detail view in perspective of said second embodiment.

Figure 6 is a top view of a third embodiment. Figure 7 is an end view thereof, and

Figure 8 a detail view in perspective of the bottom thereof.

Figure 9 shows a modification of the partitioning inner-frame, and

Figure 10 shows another way of forming the skeleton-frame of the case.

In all these figures, A indicates generically the bottom of the case, B the end-walls and C the longitudinal walls thereof, D the inner-partitioning frame and E the bottles.

In the first embodiment (Figures 1 and 2), the bottom A comprises two U-shaped end-channels 10, lying on a bottom-side provided with an inner upturned flange 11, cut short at both ends, two outer strips of timber 12 provided near their ends with inner vertical L-shaped slots 13 and outer vertical grooves 14, two inner strips of timber 15 with horizontal bottom-grooves 16 engaging the flanges 11 and six tie-pieces of timber 17, inserted endwise within the channels 10. All these parts are tied longitudinally together by means of three wires 18, riveted at both ends 19. These wires serve also as supports for the necks 20 of the bottles E, when the latter are turned upside-down in the case for draining purposes after washing.

When assembled, all these parts 10 to 19 form a solid frame, which may be then readily engaged as a whole, horizontally and downwardly along four upright corner-guides, fitting into the slots 13 and the grooves 14. Each of these guides comprises an inner angle-iron 21, provided with four slots 22 and an outer angle-iron 23, with bottom 24 and two upturned flanks 25, 26 of said bottom. Said angle-iron 23 is furthermore provided with two inwardly turned vertical flanges or reinforcing ribs 27, 28. The flange 27, which fits into the groove 14, extends on the whole height of the iron 23, while the flange 28 is curtailed just above the channel 10.

Near the end of this inserting movement, the four flanks 26 are slightly repulsed, i. e. opened, by the channels 10 of this frame, acting then as

wedges between the flanges 28 and the angle-irons 21, but as soon as the frame reaches the bevelled ends 29 of said flanges 28, these flanks 26 act as snapping-springs and press said frame and said 5 four upright guides together in their proper relative position.

The two longitudinal walls are then formed by inserting one after the other five strips of timber 30, 31, 32, 33 and 34 between the front and the 10 rear pairs of upright-guides 21, 23 respectively. Each of these strips is provided at both ends with outer vertical grooves registering with the grooves 14 and engaging the flanges 27 of the angle-irons 23. The two end-walls B are afterwards formed 15 likewise with strips of timber 35. The three lower strips 35 are provided with two vertical inner grooves 36 and two outer vertical grooves 37, while the two upper strips 35, in which are formed the usual handles (not shown), present only these 20 latter grooves 37 engaging the flanges 28 of the angle-irons 23.

The all-wood inner partitioning frame D for holding the bottles properly spaced apart comprises six posts of timber 38 assembled by means 25 of any convenient mortise and tenon joint without any fastening, with two pairs of longitudinal tie-slats 39 and three pairs of transversal tie-slats 40, so as to form a wood unit extending over the height of the three lower strips 30, 31 and 32. 30 This unit may be readily inserted downwardly into the case before the insertion of the two pairs of upper strips 35 of the end-walls B, the end of the tie-slats 39 engaging into the opposite grooves 36.

35 When the parts A, B, C, D of the case are thus assembled, eight pairs of rivets 41 are engaged into the holes 42 of the outer angle-irons 23, registering with the slots 22 of the inner angle-iron 21 and with holes (not shown) of the strips 30, 40 34 and corresponding end-strips 35.

To replace or repair the bottom A, which is the most vulnerable part of the case, one has only to cut these sixteen rivets 41 and to remove the four side-walls B, C of the case and afterwards the 45 bottom A.

If a part only of this bottom is to be replaced, there is no dismounting required for the strips 12 and only the cutting of the one riveted end 19 of one wire 18 to allow the removal of either 50 of the strips 15.

To change or repair either of the side-walls B, C, it is only necessary to cut the upper two rivets on that wall in order to remove the upper four strips of timber of each wall, and to cut the 55 four rivets of that wall to remove all the strips, while to remove the inner frame D, one has only to cut the two upper rivets of each end-wall B and to remove the two pairs of upper end-strips 35.

60 The bottom A in the second embodiment (shown in Figures 3 to 5) is framed by a U-channel 43 closed on itself, and comprises—as in the first embodiment—two pairs of outer and inner strips of timber 44 and 15 and three tie-rods or wires 18. 65 Each strip 15 is provided at each end with a bottom-groove 16 engaging the end-flanges 11 of the U-channel 43. Each of said wires 18 is slidably mounted into the channel 43 by means of U-shaped slides 45 soldered at its ends.

70 Each upright guide-corner is made of a one-piece angle-iron 46, 47, 48 the lower of which fits exactly around a corner of the U-channel 43. An opening or slot 49 is provided in said channel 43 to allow the end-wise insertion therein, one 75 after the other, of all the bottom parts 15, 18, 44.

The side-walls C, B are formed with strips of timber 50, 51, as in the first embodiment, but these strips have no outer groove, only the three lower strips 51 have inner vertical grooves to hold the inner frame D fast within the case.

80

In this embodiment, said inner frame D comprises six octahedral wooden posts 52, held in vertical position at the proper spacing by means of two pairs of longitudinal tie-slats 53, and three pairs of transversal tie-slats 54, and furthermore ten end posts 55, kept pressed against the inside walls of the case by the lower pairs of slats 53, 54 and held against vertical displacement by the upper pairs of slats 53, 54.

85

63 (Figure 4) indicates the usual openings in the end-walls B serving as handles.

90

It must be noted that in said embodiment, it is not necessary to remove the channel member 43 in order to replace another part of the bottom A as, after removal of the two double angle-irons 46, 48 on the longitudinal side where is the opening 49, all of these other parts may be withdrawn one after the other, simply by being first slid along the end-sides of the channel 43 in the direction of the arrow Y (Figure 3) and then pulled endwise in the perpendicular direction X through the opening 49 as shown in Figure 5.

95

It must be noted also that in this embodiment the parts forming the bottom A are assembled in a self-contained unit, without any fastening.

100

In the third embodiment (Figures 6 to 8), the interior of the open-bottom A is formed by three pairs of parallel wires 57, stretched between the two end-sides of a U-channel 56 and riveted thereto at 58. The inner-frame D comprises six vertical wooden posts 59, kept in spaced relation by means of a netting of perpendicular wires 60, 61 secured to the side-walls B, C of the case. A reinforcing cross U-channel 62 (Figure 7) is suitably secured to the channel 56 in order to keep 115 the wires 57 at the proper spacing.

105

In these two last embodiments, the four one-piece double angle-irons 46, 48 give such a rigidity and strength to the lower part of the case that the lower row of rivets 41 may be dispensed 120 with.

110

Thus, the walls A, B, C of the case are fastened together by only eight upper rivets.

115

In order to minimize the rattling of the bottles, due to the play between them and the surfaces of contact of their compartments, the partitioning inner-frame may be conveniently formed by parallel rows of individual holders 64 (Figure 9), consisting of two crossed U-shaped straps of spring-steel fastened together and to the bottom 130 A of the case by means of rivets 65.

125

In that case, three strips of timber 66 similar to the strips 15 replace the three wires 18 of the bottom A, the strips 15 and 44 may be dispensed with if the all-around U-channel 43 or 56 is used 135 and six tie-pieces similar to the pieces of timber 17 are used to hold said strip 66 fast at the proper spacing.

130

The straps 64, instead of being cut as shown at their outwardly bent ends, may be continuous and undulated from one side of the case to the opposite side, so as to form the desired number of bottle-holders equally spaced and arranged in parallel rows in the case.

140

Figure 10 shows a modification of the skeleton-frame formed by the bottom A and the four upright angle-irons, reinforcing the corners of the case and serving as guides for the insertion of the side-walls B, C. According to this modification, in order to still further stiffen the case, the 150

145

channel-member 67 reinforcing each end-side of the bottom A and the two adjoining upright guide-members 68 are formed from a single strip of metal 69, conveniently stamped and folded as shown in dash and dot lines. By the same stamping operation are formed twelve rivet-holes 42 and the three holes 70 for the wires 18, while by suitable folding operations are formed the two upturned flanks 26 and the inner-flange 11. Thus 5 is obtained a very strong and rigid skeleton-frame for the case.

It must be noted that in all the embodiments of the invention shown on the drawings, the channel-member does not only reinforce the sides of the case, but furthermore serves as a positive carrier or holder for the constitutive parts of the bottom A.

In order to further reduce the breakage of bottles, all or part of the surfaces contacting with said latter may be permanently covered or coated with a layer of more or less soft substance as rubber or leather, or strips of rubber may be stretched across the bottom and sides of the case. The wires 18, 57, 60, 61 may be likewise wrapped 20 with similar substances or surrounded with tubes made of them.

Variations may be resorted to within the scope of the invention and portions of the improvements may be used without others.

30 A bracing tie-member, similar in effect to the cross U-channel 62, may be secured across the middle of the bottom A in all the embodiments shown in order to prevent the breaking of bottles when loading the cases on a hand-truck.

35 Having thus described my invention, I claim:
1. A bottle case comprising two metal frames, each of said frames being made out of one piece of sheet metal and bent to form a bottom channel and two uprights, an inner, upturned flange in each channel, grooved strips located between the channels to constitute part of the bottom of the case, the grooves of said strips to engage the upturned flanges of said channels, inner upturned

flanges on each upright, grooved strips located between the uprights to form the walls of the case, the grooves of said strips to engage the upturned flanges of said uprights and means to secure said frames and strips relative to each other to constitute a rigid and durable bottle case.

2. A bottle case comprising two U-shaped metal frames, each of said frames being made out of one piece of sheet metal and bent to form a bottom channel and two angle uprights, strips and tierods between the channels to form the bottom of the case with said channels, means to retain the ends of said strips within said channels, strips located between the uprights to form the walls of the case, the strips at the extreme ends of the uprights being secured to said uprights.

3. A bottle case comprising two U-shaped metal frames, each of said frames being made out of one piece of sheet metal and bent to form a bottom channel and two angle uprights, alternating strips of wood and tierods mounted between said two channels to form therewith the bottom of the case, means to retain the ends of said strips and tierods within said channels, strips of wood located between the four angle uprights to form the walls of the case, the strips at the extreme ends of uprights being riveted to said uprights.

4. A bottle case comprising two bottom channel members made integral with the adjoining upright corner members so as to form therewith a two piece self-supporting metallic skeleton frame, to which are removably fastened the four wooden side-walls of the case, each of said channel members in one piece with the two adjoining reinforcing upright corner members being formed by a single stamping operation and five folding operations from a single strip of metal, with all the necessary rivet-holes, with two upturned flanks fitting in corresponding slots of the bottom and with an inner flange engaging corresponding grooves provided in said bottom.
